(57) **CLAIM**

The ornamental design for an industrial impact safety glove,
as shown and described.

DESCRIPTION

FIG. 1 is a perspective view of an industrial impact safety
glove in accordance with the present design;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown are included for the purpose of
illustrating a portion of the industrial impact safety glove
that forms no part of the claimed design.

Although shown in the context of a right hand glove, an
embodiment of the present invention is also incorporated in
a left hand glove, wherein the left hand glove is a mirror
image of the right hand glove depicted in the FIGS. 1 to 7.
